PORTABLE FIREPLACE STOVE

Wendell H. Lovett, 14445 SE. 55th St., Bellevue, Wash.

Filed July 15, 1965, Ser. No. 86,167

Term of patent 14 years

(Cl. D81—7)

FIG —1

I claim:

The ornamental design for a portable fireplace stove, substantially as shown.
